UNITED STATES PATENT OFFICE.

ROBERT C. STOEWSAND, OF CHICAGO, ILLINOIS.

COMBINED FUNNEL AND MEASURING-RECEPACLE.

No. 853,427.

Specification of Letters Patent.

Patented May 14, 1907.

Application filed February 20, 1906. Serial No. 302,127.

To all whom it may concern:

Be it known that I, ROBERT C. STOEWSAND, a citizen of the United States, residing at Chicago, in the county of Cook and State 5 of Illinois, have invented certain new and useful Improvements in Combined Funnels and Measuring-Receptacles, of which the following is a specification.

This invention relates to improvements in 10 receptacles for measuring and handling liquids; and has among the salient objects of its invention to provide improved means for allowing the fluid to escape through a funnel in the bottom of the receptacle; to provide 15 means whereby the funnel is supported out of contact with the surface on which the receptacle rests; to provide a construction which will serve the purpose of an ordinary funnel and at the same time stand in an 20 upright position on the surface on which it is placed; to provide an improved device whereby the plug-valve is easily removed from or inserted in the funnel; to provide an 25 extremely economical and effective construction, the mechanism of which is not only conveniently arranged to permit the filling of the receptacle but is easily and readily cleaned; and in general to provide an improved construction of the character referred to.

30 I am aware that devices have been patented in which the liquid is allowed to escape through the bottom of the receptacle, and in which valves controlled by spring pressed levers have been employed to regulate 35 this escape. My invention has to do with improvements in the construction and arrangement of such devices. The particular advantages of my construction will more clearly appear in the following description, 40 reference being had to the accompanying drawings, in which—

Figure 1 is a perspective view of the receptacle showing the spring pressed lever and plug in position in the funnel. Fig. 2 is an 45 axial sectional view of a portion of the receptacle, showing the plug within the funnel.

In the drawings 1 designates as a whole the receptacle which may be graduated as a measure or not as desired, having a handle 2, 50 a bottom 3, and a down standing flange 4, on which the receptacle stands. The bottom 3 converges downwardly from the side of the vessel toward its center, which is cut away to permit the attachment of a funnel 5. In 55 order that all the liquid may flow through this funnel it is thus placed at the lowest part

of the sloping bottom and has its top flush with the bottom of the vessel. A plug valve 6 is conveniently shaped to fit tightly within the funnel 5 and may be readily removed or 60 inserted by means now to be described. This valve, as conveniently made, comprises a disk portion 6, provided with an annular plug-flange fitting the funnel, a head 7 having an extension which passes through the 65 disk, and a sleeve fitting over the extension of the plug and against the under side of the disk, said sleeve and extension being rigidly united. The head 7 has a transverse opening 8 through which is inserted the lower end 70 of a connecting rod 9. This rod 9 is shaped substantially in a double reverse curve as shown clearly in Fig. 1. Its lower end is inserted into the opening 8 of the plug, then bent to an obtuse angle and extends diagonally up to and rests in sliding contact with the side of the vessel to which the handle 2 is attached; from thence the rod is bent inwardly and continues diagonally upwardly and toward the center of the vessel until it 80 nearly reaches the top of the latter when it is again bent toward the handle side of the vessel.

The object of shaping the rod in the manner just described is to guide it in its upward 85 and downward movement by its engagement with the side of the receptacle and to place it as far as possible out of the way when the receptacle is being filled, as will more clearly appear hereafter. To actuate this rod I provide 90 a spring-pressed thumb-lever 10 pivotally mounted on, and in alinement with, the handle of the vessel, as at 11, and provided at the under side of its outer end with a coiled spring which is suitably fastened to the handle 95 2. The opposite end of this lever is pivotally connected with the upper end of the arm 9, at 13. The coöperating action of these parts is one of the features of my invention. If the lever-pivot alone were 100 used and the connecting arm rigidly connected to the lever, the plug would on raising the arm bind against that portion of the funnel opposite the handle side of the vessel. The use of the second pivot, at 13, prevents 105 this binding as that portion of the arm which is in contact with the side of the vessel will now on the pressing down of the thumb-lever slide along and be guided by the side of the vessel and a direct upward force will be applied to the plug.

As heretofore noted the bottom of the

vessel is provided with a down turned flange which preferably is one piece with the side of the receptacle. This flange is cut away at 14 so as to be readily set over the handle 5 of a jug or similar vessel which is to be filled. An opening 15 is cut in the flange so that the funnel can be readily viewed when the receptacle is being used to conduct liquid to another vessel.

10 The operation of the device is obvious, the receptacle being filled with liquid to be conducted to another vessel is held by the handle and placed over the receptacle to be filled. The lever is now pressed down by 15 the thumb, actuating the connecting arm and removing the plug from the funnel. As soon as the liquid has run out the pressure is removed from the lever and the spring at once forces down the actuating arm which 20 in turn forces the plug into position in the funnel.

I claim as my invention:

A combined measuring cup and funnel comprising a generally-cylindric cup-like receptacle provided with a downwardly-converging bottom having at its middle portion

an outlet formed through it, a stopper or plug-valve fitting said outlet, an operating rod rigidly connected with said stopper, bent to extend thence to, and arranged to slide 30 and bear against, the vertical side wall of the cup intermediate the depth of the latter and extended thence up to the top of the cup, a thumb-lever pivoted between its ends to the upper margin of the cup and having one end 35 pivotally connected to the end of said operating rod, a handle attached to the side of said receptacle, a spring interposed between the upper part of said handle and the thumb-piece of said thumb-lever, a funnel connected 40 to the bottom of the cup and surrounding said outlet, a supporting rim or flange formed in continuation of the side-body of the cup and extending below the lower end of the funnel, and a peephole formed through said 45 flange and exposing the delivery end of the funnel to view.

ROBERT C. STOEWSAND.
